Primary Examiner — Eric L Goodman*Assistant Examiner* — Carissa C Fitts*(74) Attorney, Agent, or Firm* — Lawrence N. Ginsberg(57) **CLAIM**

The ornamental design for an orthotic device, as shown and described.

DESCRIPTION

FIG. 1 is a top perspective view of the orthotic device, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of portions of the orthotic device, forms no part of the claimed design.

1 Claim, 6 Drawing Sheets(56)
